UNITED STATES PATENT OFFICE.

CHARLES W. ROGERS, OF CHICAGO, ILLINOIS, ASSIGNOR OF SIXTY-NINE ONE-HUNDREDTHIS TO JULIAN W. MATHIS, EUGENE WORTIIING, AND CRAMPTON L. LINLEY, OF CHICAGO, ILLINOIS.

RADIATOR.

SPECIFICATION forming part of Letters Patent No. 702,483, dated June 17, 1902.

Application filed January 22, 1900. Serial No. 2,333. (No model.)

To all whom it may concern:

Be it known that I, CHARLES W. ROGERS, a citizen of the United States, residing at Chicago, in the county of Cook and State of Illinois, have invented certain new and useful Improvements in Radiators, of which the following is a specification.

Steam and other radiators for transmitting heat and for other purposes as now constructed are of two distinct and well-known types or forms of construction, one having a body or tubular portion composed of wrought-iron pipes entered into headers either of wrought or cast iron and the other having a body or tubular portion and the headers made integral and of cast metal. Both constructions are expensive to make and somewhat cumbersome and heavy to handle.

The object of my invention is to construct steam and other radiators on a different plan from the practice heretofore and which shall combine cheapness and economy as regards construction with efficiency and durability in operation; and the invention consists in constructing from a single plate or from two half-plates of wrought metal a radiator as an entirety comprising a plurality of tubes in a continuing series or set and the headers, such plate or plates being struck, stamped, pressed, or otherwise formed into shape to present a half-section of the complete radiator, each half-section having a plurality of vertical half-tubes and in a continuous set or series integral with a horizontal half-header and having also edge flanges and inner contact-faces for the two half-sections when brought together and united by welding or otherwise uniting the abutting edge flanges and the contact-faces to produce a completed radiator having a body or tubular portion and headers with the body composed of a plurality of tubes and the headers joined directly with and forming part of the tubes at the top and bottom, as hereinafter described and claimed.

In the drawings, Figure 1 is a side elevation, broken out at the center, showing my improved construction of radiator; Fig. 2, an end elevation, likewise broken out at the cen-

ter; Fig. 3, a transverse section on line 3 of Fig. 1; Fig. 4, a detail in section on line 4 of Fig. 2; Fig. 5, a side elevation, broken out at the center, showing my improved construction of radiators with the tubes and headers made from a single plate by bending the plate on itself centrally to form one of the headers and showing also the induction and eduction pipes and the plugs for closing the ends of the headers opposite the induction and eduction pipes; Fig. 6, an end elevation of the construction shown in Fig. 5; and Fig. 7, a longitudinal section through the header of Fig. 5, formed by bending the plate on itself.

In constructing my improved radiator I provide a body or tubular portion A with headers B therefor, and, as shown, each header is provided at its ends with a reinforcing tube or thimble C for the purpose of attaching the radiator to a steam or other supply pipe D at one header and to a discharge-pipe D' at the other header, as shown in Fig. 5. The opposite end of each header to that for the attachment of the pipes is to be closed by a suitable plug or cap E, as shown in Figs. 5 and 7, screw-threaded or otherwise entered into the reinforcement or thimble C in any usual or well-known manner, or it can be permanently closed by a continuous seam. The body or tubular portion and the headers are struck or formed integral in sections or halves from plates of wrought metal, for which purpose a plate of the requisite dimensions for the size of radiator is provided for each half or section. Each plate where two plates are employed for a radiator is struck or otherwise formed so as to have depressions, preferably semi-oval or semicircular in cross-section, which when brought together form the tubes A, as shown in Fig. 3, and each plate has at its end or edge a flange or lip a or other suitable welding or joining face or edge, and between each depression is a contact-face a'. The headers are each formed at the end of the tube by a depressed portion in each plate into which the tubular or depressed portions of the body enter, so that when the two plates are brought together a complete whole is

formed having a body or tubular portions with tubes and a header at each end of the tubes. Each header has a flange or lip *b* or other suitable welding or joining face or edge 5 on its outer side in vertical alinement with the edge or lip *a*. The two plates are brought together so as to have the edges or lips *a* and the edges or lips *b* in engagement and also to have the contact-faces *a'* in engagement, 10 and in this position the two plates are united together, preferably by electric welding, so as to form a close union between the flanges or lips *a*, the flanges or lips *b*, and the contact-faces *a'*, making a complete whole out of the 15 two plates or halves and a complete radiator with a body or tubular portion and headers. The reinforcements or thimbles *C* may be inserted in the ends of the headers prior to welding the halves together, so as to be united to 20 the headers in the process of welding, or they may be applied and united afterward, each reinforcement or thimble having the ends screw-threaded or of other form of construction for attachment of the pipes or the insertion 25 of the end plugs or caps. The employment of two separate plates for constructing the radiator is not an absolute necessity, as it is evident that a single plate of the requisite dimensions can be used, such plate being 30 stamped or pressed into shape to have a body or tubular portion on each side of its center formed of depressions, contact-faces, a depressed portion at the edges or sides, and end and side flanges or lips, with the intermediate portion or center between the two 35 bodies formed so that by bending the plate at the center, a header will be formed at that point, as shown in Figs. 5 and 6, the opposite header being formed by the depressed 40 portions at the sides or edges. The radiator as a whole is completed by bringing the two halves together and joining them by uniting the flanges or lips and the contact-faces, as before described. As will be understood, then, 45 when I speak of "halves" or "sections" I contemplate forming them of either a single piece of metal or separate pieces, as desired. The radiator thus formed is of great simplicity and economy as regards construction, as it 50 can be readily and quickly formed by stamping or pressing the metal plate halves or sections so as to have edges, flanges or lips, and intermediate contact-faces and then uniting the two halves or sections by electric welding 55 or otherwise, so as to make a close union between the edges, flanges or lips, and the contact-faces. The welding or joining of the flanges or lips should be such as to make a steam-tight joint; but for the union between 60 the inner or intermediate contact-faces the joint need not be steam-tight. The radiator can be made from light wrought-iron or metal plates, and when stamped into shape and the parts united will possess greater rigidity and 65 strength than the ordinary constructions of

radiators, and by using light metal plates a radiator can be formed which will be light and at the same time very strong and durable, and this form of radiator is applicable to all purposes for which radiators are used, 70 but especially for heating and ventilating by any ordinary fan system.

I claim—

1. A radiator consisting of a body or tubular portion and headers, the body or tubular portion embracing, as a unit, a plurality of tubes, and having the entire series of body-tubes with the headers made from two companion plate halves or sections, each stamped or pressed into shape to form a multiplicity 75 of straight-line body depressions, with the body depressions of one plate half or section in alinement with and parallel with the body depressions of the companion plate half or sections, the two series of body depressions 80 running in straight lines across the plate halves or sections and to form on two opposite sides edge depressions with the edge depressions of one plate half or section in alinement with and parallel with the edge depressions 85 of the companion plate half or section the two sets of edge depressions running in a straight line and in a right-angle relation to the body depressions and intersecting the ends of the body depressions, each body depression 90 constituting one-half of a straight-line body-tube and each edge depression constituting one-half of the straight-line header integral with the half-tubes of the body, and to form edge flanges on the sides and ends of 95 the plate halves or sections and interior contact-faces on the sides of the body-tubes, for the two plate halves or sections to be joined together by uniting the flanges and contact-faces, substantially as described. 100

2. A radiator consisting of a body or tubular portion and headers, the body or tubular portion embracing, as a unit, a plurality of tubes, and having the entire series of body-tubes with the headers made from two companion plate halves or sections, each stamped or pressed into shape to form a multiplicity 105 of straight-line body depressions, with the body depressions of one plate half or section in alinement with and parallel with the body 110 depressions of the companion plate half or section, the two series of body depressions running in straight lines across the plate halves or sections and to form on two opposite sides edge depressions with the edge depressions 115 of one plate half or section in alinement with and parallel with the edge depressions of the companion plate half or section the two sets of edge depressions running in a straight line and in a right-angle relation to the body 120 depressions and intersecting the ends of the body depressions, each body depression constituting one-half of a straight-line body-tube and each edge depression constituting one-half of a straight-line header integral 125

with the half-tubes of the body, and to form
edge flanges on the sides and ends of the
plate halves or sections and interior contact-
faces on the sides of the body-tubes, for the
5 two plate halves or sections to be joined to-
gether by uniting the flange and contact-
faces, and a reinforcement or thimble at each

end of each header, substantially as de-
scribed.
